UNITED STATES PATENT OFFICE.

CHARLES V. MCINTIRE, OF NEW YORK, N. Y., ASSIGNOR, BY DIRECT AND MESNE ASSIGNMENTS, OF ONE-THIRD TO LOUIS WILPUTTE AND TWO-THIRDS TO ALICE A. WILPUTTE, BOTH OF NEW ROCHELLE, NEW YORK.

COKE-OVEN-REGENERATOR CONNECTION.

1,292,623.

Specification of Letters Patent. Patented Jan. 28, 1919.

Application filed July 3, 1917. Serial No. 176,331.

To all whom it may concern:

Be it known that I, CHARLES V. MCINTIRE, a citizen of the United States of America, residing in the city, county, and State of New York, have invented certain new and useful Improvements in Coke-Oven-Regenerator Connections, of which the following is a true and exact description, reference being had to the accompanying drawings, which form a part thereof.

My present invention comprises improvements in the valved connections to the regenerators of coke ovens, and the object of the invention is to provide an improved connection for the purpose specified characterized by its simplicity and effectiveness, and particularly by the comparative ease with which it may be assembled and taken apart, and installed and replaced or adjusted when the severe operating conditions to which such connections are subjected make such replacement or adjustment necessary.

The various features of novelty which characterize my invention are pointed out with particularity in the claims annexed to and forming a part of this specification. For a better understanding of the invention and the advantages possessed by it, reference should be had to the accompanying drawings and descriptive matter in which I have illustrated and described a preferred embodiment of my invention.

Of the drawings:

Figure 1 is a sectional elevation of a portion of a coke oven, the section being taken on the broken line 1-1 of Fig. 3.

Fig. 2 is a section on the line 2-2 of Fig. 1.

Fig. 3 is a sectional plan taken on the line 3-3 of Fig. 1.

Fig. 4 is a view taken similarly to Fig. 1, illustrating a modified construction, and

Fig. 5 is a section taken on the line 5-5 of Fig. 4.

In the drawings, and referring first to the construction shown in Figs. 1, 2 and 3, I have illustrated the use of my invention in connection with a coke oven of the type disclosed and claimed in the patent to Louis Wilputte, No. 1,212,866, granted Jan. 16, 1917.

It will be apparent to those skilled in the art that the utilization of the present in-

vention in general does not depend upon the shape, distribution or character of the regenerators with which they are used.

In the type of coke oven referred to above there are a series of regenerators arranged side by side beneath and extending transversely to the coking chambers, each regenerator being made up of series of alternately disposed sections A' and A² of greater and less horizontal cross section. Beneath the regenerators and extending transversely to the latter are a series of off-take passages or sole channels A³, each of which communicates with the regenerators above it through ports A⁴. Along side the passages A³ are passages A⁵, in each of which is located a supply pipe B. Each supply pipe B is formed with a plurality of discharge ports B', which deliver air into the regenerative spaces A' above the ports B' through ports A⁶ in the bottom wall of the regenerator spaces A'. The off-take channels A³, and supply pipes B extend into the oven battery A from each side edge of the latter. Along each of the side edges of the battery is located a tunnel or conduit main D.

The outer end of each passage A³ is connected to the adjacent tunnel D by an individual valved connection comprising a casing which in the preferred construction illustrated is formed of two readily separable casing sections E and E¹⁰. Each casing section E may be described as of inverted cup shape with a flanged rim E² which rests on the top wall of the tunnel D. The open lower end of each casing member E is in communication with the tunnel D through a corresponding port D² of the latter. At its side adjacent the coke oven each casing E is formed with an aperture through which the outer end of the corresponding casing element E¹⁰ extends. The latter is formed with a peripheral flange E¹²,

which in the assembled condition of the casing abuts against the margin of the aperture in the casing section E through which the casing element E¹⁰ extends. The two cooperating casing sections E and E¹⁰ are detachably secured together by bolts E¹³ passing through the casing element E¹⁰ and a flange E' on the casing element E which surrounds the rib E¹². Advantageously the

joint between the flange E' and the casing element E¹⁰ is sealed as by means of a rust point luting F¹⁰.

Each casing section E¹⁰ is connected to the outer end of a corresponding off-take channel A², and in the preferred construction illustrated the connection is a telescopic one. For this purpose the outer end of each channel A² is enlarged, as indicated at A⁷, to receive the end of the corresponding casing section E¹⁰, and the clay luting F sealing the joint between the casing section and the end of the channel A². The joint between the lower end of the casing section E and the corresponding port D² is preferably sealed by clay luting F, and in the construction shown in Figs. 1 and 2 the upper wall of the tunnel D is recessed at D', about the margin of each port D², to receive the lower end of the corresponding casing element E, and the luting clay around the latter. The recess D' is preferably large enough to permit sufficient horizontal movement of the casing section E therein to allow of the removal of casing section E and its replacement without disturbing the connection between the corresponding casing section E¹⁰ and the masonry structure of the oven.

The end of each casing section E¹⁰ projecting into the corresponding casing section E is faced off to form a valve seat E¹¹ against which a corresponding valve body H seats when communication between the corresponding off-take passage A² and tunnel D is closed. Each valve H, in the construction illustrated, is in the form of a metal plate provided on its back with lugs H', receiving a pin H², by means of which the valve member is connected to valve operating arms I. The latter are secured to a valve operating rock shaft I², journaled adjacent its ends in the opposite walls of the corresponding casing section E. Externally of the casing section E an operating arm I² is secured to the rock shaft I². The arm I² is connected by a link J² to one arm of a corresponding bell crank lever J, which is pivotally mounted at J² on an adjacent oven back stay C. The second arm of the lever J is connected in the usual manner to the reversing cable or rod K running along the corresponding side of the battery. The arms I are formed with shoulders I' adjacent their free ends. The sides of these shoulders adjacent the corresponding valve body lugs H' are parallel to the adjacent ends of the latter, but are separated therefrom by a slight clearance space. This permits a limited movement of each valve member H relative to its supporting arm I which is desirable to permit the proper seating of the valve member, but prevents an undesirable displacement of the valve member relative to its supporting arms. The flow out

of each outlet passage A² when the corresponding valve member H is in its open position may be regulated by the usual slide damper G adjustably held in any desired setting by the pin G'.

In the construction shown, each tunnel D is operated alternately as an off-take conduit into which the corresponding set of off-take sole channels A² discharge, the valves H being then open, and as a supply main through which the air to be preheated in the regenerators is distributed to the various air supply pipes B. In the preferred construction illustrated each valve casing section E and the corresponding port D² 70 75 80 85 90 95 100 105 110 115 120 125 130 135 140 145 150 155 160 165 170 175 180 185 190 195 position in which it does not obstruct communication between the casing sections E¹⁹ and E²⁰. The valve casing section E²⁰ is like the valve casing section H of the construction shown in Figs. 1 and 2, except that the top of the valve casing member E²⁰ is made relatively higher to compensate for the fact that the valve member H¹⁴ cannot move as close to the top wall of the casing E²⁰ as the valve member H can move to the top of the casing E. The elbow L¹⁴ differs from the elbow L only in being curved to compensate for the relatively greater elevation of the port E² in Figs. 4 and 5.

15 Coke oven regenerator connections are subjected to severe disturbing effects by the thermal expansion and contraction of the oven structure and adjuncts, and particularly of the masonry portion thereof. Thermal expansion and contraction causes marked relative changes in position of different parts of the oven structure to occur, and such changes continue to occur throughout practically the entire operating life of the oven. My improved regenerator connections are obviously well adapted for easy and accurate realignment from time to time as well as for the maintenance of tight joints, as the oven parts change in form or relative arrangement as a result of unequal expansion and contraction. The use of the pivoted valve member H connected to the reversing mechanism proper, in the simple manner described, minimizes the disturbing effects on the operations of the valves of irregular movements of the latter resulting from expansion and contraction of the oven structure.

While in accordance with the provisions of the statute I have illustrated and described the best forms of my invention now known to me it will be apparent to those skilled in the art that changes may be made in the form of the apparatus disclosed without departing from the spirit of my invention, and that certain features of my invention may sometimes be used to advantage without a corresponding use of other features.

Having now described my invention, what I claim as new and desire to secure by Letters Patent, is:

1. In a coke oven, the combination with a vertical regenerator wall and the top wall 55 of a horizontal conduit running alongside said vertical wall, of a valved connection between said regenerator and conduit comprising a metallic casing formed of two separable sections, one having one end anchored 60 in said vertical wall and the other having one end anchored in said top wall.

2. In a coke oven, the combination with a vertical regenerator wall and the top wall 65 of a horizontal conduit running alongside said vertical wall, of a valved connection be-

tween said regenerator and conduit comprising a metallic casing formed of two separable sections, one connected to said vertical wall and the other connected to said top wall, said walls being each recessed to receive the corresponding casing section and luting material for sealing the joints between the sections and walls.

3. A coke oven structure comprising a series of regenerators, a series of regenerator supply conduits and a series of regenerator offtake passages separate from said supply conduits, and in combination therewith a tunnel running alongside the regenerators and alternately usable as an offtake and as main supply, and a bifurcated connection leading from said tunnel to each of said offtake passages and an adjacent one of said supply conduits.

4. A coke oven structure comprising a series of regenerators, a series of regenerator supply conduits and a series of regenerator offtake passages separate from said supply conduits; and in combination therewith a tunnel running alongside the regenerators and alternately usable as an offtake and main supply, and a bifurcated connection leading from said tunnel to each of said offtake passages and an adjacent one of said supply conduits, and a valve controlling flow through one leg of said bifurcated connection.

5. A coke oven structure comprising a series of regenerators, a series of regenerator supply conduits and a series of regenerator offtake passages separate from said supply conduits, and in combination therewith a tunnel running alongside the regenerators and alternately usable as an offtake and main supply, and a bifurcated connection leading from said tunnel to each of said offtake passages and an adjacent one of said supply conduits, and a single valve for opening and closing one leg of said bifurcated connection, and simultaneously closing and opening respectively the other leg of said bifurcated connection.

6. A coke oven structure comprising a series of regenerators, a series of regenerator supply conduits and a series of regenerator offtake passages separated from said supply conduits, and in combination therewith a tunnel running alongside the regenerators and alternately usable as an offtake and main supply, and a bifurcated connection leading from said tunnel to each of said offtake passages and an adjacent one of said supply conduits, and means for opening and closing one leg, and simultaneously closing and opening respectively the second leg of said bifurcated connection.

7. In a coke oven structure, the combination of a row of regenerator outlet valves, each comprising a valve casing, a rock shaft projecting through the casing, an oscillat-

4

ing valve member connected to said rock shaft within the casing, and an operating arm secured to said rock shaft externally of the casing, a row of operating levers 5 mounted on the oven structure, and connected each to a corresponding one of said valves, and means for simultaneously oscillating said levers.

8. A coke oven regenerator connection 10 comprising a casing formed with two ports at an angle to one another, and a valve mem-

ber journaled in said casing to turn about an axis parallel to the axis of one of said ports and comprising a portion transverse to said axis and controlling one of said ports 15 and a second portion parallel to said axis and controlling the other of said ports, said ports and valve member being so relatively arranged that each of said ports is open when the other is closed.

CHARLES V. McINTIRE.
